WINE GOBLET

Thomas H. Stott, Pleasant Hill, Calif., assignor to IMS Corporation, Albuquerque, N. Mex.

Filed Apr. 18, 1972, Ser. No. 245,295

Term of patent 14 years

Int. Cl. D7—01

U.S. Cl. D7—13

FIG. 1.

FIG. 2.

FIG. 3.

FIG. 4.

FIG. 1 is a top perspective view of a wine goblet showing my new design;

FIG. 2 is a side elevational view thereof, a portion of which is shown fragmentarily for convenience of illustration;

FIG. 3 is a top plan view thereof; and

FIG. 4 is a bottom view thereof.

I claim:

The ornamental design for a wine goblet, as shown and described.
